DISPENSING CONTAINER

Joseph E. Brady, West Chester, and Howard E. Curtis,
Perkasie, Pa., assignors to American Home Products
Corp., New York, N.Y.

Filed Feb. 28, 1975, Ser. No. 554,285

Term of patent 14 years

Int. Cl. D9—01

U.S. Cl. D9—2

FIG. 1

FIG. 2

FIG. 3

FIG. 4

FIG. 5

FIG. 6

FIG. 1 is a front view of a dispensing container showing our new design;

FIG. 2 is a top view thereof;

FIG. 3 is a bottom view thereof;

FIG. 4 is an exploded front view of the container of FIG. 1 showing the cover removed;

FIG. 5 is a top view of the container with the cover removed; and

FIG. 6 is a bottom view of the cover when removed from the container.

We claim:

The ornamental design for a dispensing container, substantially as shown.
